ATTORNEYS

UNITED STATES PATENT OFFICE.

HARRY W. GREENBRIER, OF NEWARK, NEW JERSEY, ASSIGNOR, BY MESNE ASSIGNMENTS, TO THE GREIST MANUFACTURING COMPANY, A CORPORATION OF CONNECTICUT.

SAFETY RAZOR.

Application filed August 4, 1920. Serial No. 401,135.

To all whom it may concern:

Be it known that I, HARRY W. GREENBRIER, a citizen of the United States, residing at Newark, county of Essex, and State 5 of New Jersey, have invented certain new and useful Improvements in Safety Razors, of which the following is a full, clear, and concise description.

The present invention relates to improvements in safety razors of the so-called hoe type, such as described in Letters Patent 10 No. 1,254,037, granted January 22, 1918, on an application filed by me for improvements in safety razors, and its general object is to provide a device of a simplified and efficient construction, which may be made in a minimum number of operations so as to permit of economical production with a consequent low selling price.

20 A further object of my invention is to provide a safety razor as aforesaid, in which the blade clamping element is separable from the blade carrier and is so formed as to cooperate therewith, by the manipulation 25 of the handle of the razor, to rigidly clamp or hold the blade in cutting position relatively to the guard formed integral with the blade holder.

My invention is also directed to a safety 30 razor which, by reason of the construction and separability of the components thereof, provides a device which may be cleaned with ease, owing to the accessibility of the various surfaces within which foreign matter 35 might lodge during the use thereof, thereby providing a razor which will meet the sanitary requirements of the user to the fullest extent.

Other objects and advantages of my invention will become obvious as the description 40 proceeds, and I would have it understood that I reserve unto myself all rights to the full range of equivalents, to which I may be entitled under my invention in its 45 broadest aspect.

I shall now proceed to describe my invention with reference to the accompanying drawings, and then point out with more particularity the essential elements of novelty 50 in the appended claim. In the drawings:

Fig. 1 is a view in elevation of a safety razor made in accordance with my invention;

Fig. 2 is a view in elevation, partly in section, showing the method of locking the 55 blade in shaving position.

Fig. 3 is a top plan view of the assembled blade holder with the blade in position therebetween;

Fig. 4 is a bottom plan view of the structure shown in Fig. 3;

Fig. 5 is a view looking at the underside of the clamping element, showing the position of the blade relative thereto, when in shaving position, and

Fig. 6 is a view in perspective of the blade carrier or support.

Referring now to the drawings, which illustrate one embodiment of my invention, which has been selected for the purpose of this disclosure and in which like characters 70 of reference are employed to designate similar parts throughout the several views, 7 indicates the blade carrier or support, which is stamped or pressed out of sheet metal, and which is formed with the usual guard 8. 75 The guard 8, preferably, is of an S configuration, and is of the tooth or serrated type.

As will be observed from Fig. 6 of the drawings, a portion of the blade carrier 7 80 intermediate of its ends is pressed out, as shown at 9, and is provided with an orifice 10, through which the threaded lug 11 of the clamping element 12 is adapted to project as shown in Fig. 4.

The lug 11 is formed integral with a dependent boss or protuberance 13, which may be formed up on the clamping element 12 intermediate of its ends, or may be a separate member permanently secured or united 90 thereto, by brazing or other suitable process.

The blade 14 which is of the so-called wafer type is formed with the ears 15 and 16 at each end thereof, to provide surfaces whereby the blade may be grasped between 95 the thumb and forefinger to facilitate positioning it on the clamping element 12 as hereinafter explained.

As will be seen from Fig. 2 of the drawings the major portion of the boss or protuberance 13 is spaced from the inner surface of the clamping element 12 as shown at 13^a. This space 13^a is formed to permit of the location of the blade 14 on the clamping member, so that the rear edge 14^a of the blade, which lies inwardly of the rear edges of the ears 15 and 16 may abut or bear against the retaining flange 12^a, which forms the back of the clamping element 12.

When the blade 14 is positioned on the 110

clamping element 12, as described, the clamping element is located on the blade carrier 7, the externally threaded lug 11 passing through the aperture 10 in the depressed portion 9 of the latter member. The cutting edge of the blade 14 is then in functioning position relatively to the guard 8, and the clamping element and blade carrier are drawn together to immovably clamp 10 the blade in position therebetween. This is accomplished by means of the handle 16 having a diminished upper portion 17, the end of which is provided with a recess 18 which is threaded as shown at 19. The 15 threads 19 are of the same gauge as and mesh with the external threads of the lug 11. Therefore, when the handle 16 is screwed up on the lug 11, the upper end of the handle will bear against the under surface of the depressed portion 9 of the blade carrier, causing the clamping element and blade carrier to approach each other and firmly grip the blade 14 therebetween. This 20 clamping action is obtained by the cooperation of the lug 11, the handle 16 and the depressed portion 9 of the blade carrier 7, which by reason of its formation is adapted to yield under the pressure exerted thereupon, by the upper end of the handle 16.

30 From the foregoing disclosure, it will be manifest that I have provided a simple device, which may be readily handled by the user and in which the parts may be kept

clean and sanitary after the use of the razor, by the simple expedient of disassembling 35 and wiping or rinsing the parts, the disconnection thereof affording access to every portion of their surfaces, so that it is impossible for any foreign matter to remain 40 thereon.

While, as before stated, I have described my invention with reference to the specific embodiment herein illustrated, it is obvious that various changes in the details of structure may be made, and that my invention may take other forms without departing 45 from the spirit and scope thereof.

What I claim is:

In a safety razor, a clamping element having a thickened portion intermediate of its ends formed with a slot to permit of the insertion of a blade therein, whereby the blade will lie in contact with the inner face of the clamping element, an externally threaded lug carried by said thickened portion, a blade support provided with an aperture intermediate of its edges to permit of the passage of said lug therethrough, and a handle having a recess at its upper extremity threaded for engagement with said lug, whereby the handle may be manipulated to produce pressure between said clamping element and blade support to immovably hold a blade in cutting position.

HARRY W. GREENBRIER.
